EXPANSIBLE LINK CHAIN FOR A BRACELET OR THE LIKE

Samuel Meyerson, West Hempstead, N. Y.

Application December 28, 1951, Serial No. 17,844

Term of patent 7 years

(Cl. D45—4)

To all whom it may concern:

Be it known that I, Samuel Meyerson, a citizen of the United States, residing in West Hempstead, Nassau County, and State of New York, have invented a new, original, and ornamental Design for an Expansible Link Chain for Bracelets or the like, of which the following is a specification, reference being had to the accompanying drawing, forming part thereof, in which

Figure 1 is a top plan view of an expansible link chain embodying my new design, a portion of the center being broken away for convenience of illustration only;

Figure 2 is a side elevation thereof with the conventional bottom links illustrated in broken lines;

Figure 3 is a top plan view showing the chain in an expanded position;

Figure 4 is an enlarged perspective view of one of the top links;

Figure 5 is a longitudinal section of one of the top links on line 5—5 of Fig. 4;

Figure 6 is a transverse section of the link on line 6—6 of Fig. 4; and

Figure 7 is a transverse section of the link on line 7—7 of Fig. 4.

I claim:

The ornamental design for an expansible link chain for a bracelet or the like, as shown and described.

SAMUEL MEYERSON.
